(57) **CLAIM**

The ornamental design for a combined cart-mounted display and computer for an intraoral scanner, as shown and described.

DESCRIPTION

FIG. 1 is a perspective view of a combined cart-mounted display and computer for an intraoral scanner showing a first embodiment of our new design.

FIG. 2 is a second perspective view of the first embodiment thereof.

FIG. 3 is a front view of the first embodiment thereof.

FIG. 4 is a rear view of the first embodiment thereof.

FIG. 5 is a side view of the first embodiment thereof.

FIG. 6 is a side view of the first embodiment thereof.

FIG. 7 is a top view of the first embodiment thereof.

FIG. 8 is a bottom view of the first embodiment thereof.

FIG. 9 is a perspective view of a second embodiment of a combined cart-mounted display and computer for an intraoral scanner. The front, side, top and bottom views of the second embodiment are the same as those of the first embodiment; and,

FIG. 10 is a rear view of the second embodiment thereof. The broken lines showing the cord and scanner in FIG. 9 are directed to environmental subject matter and are for illustrative purposes only, while all other broken lines are directed to portions of the combined cart-mounted display and computer for an intraoral scanner that form no part of the claimed design; the broken lines form no part of the claimed design.
